P. S. RUSSEL

1,892,190

STRAINER

Filed Feb. 25, 1928

UNITED STATES PATENT OFFICE

PHILIP SHERMAN RUSSEL, OF DETROIT, MICHIGAN, ASSIGNOR TO DETROIT LUBRICATOR COMPANY, OF DETROIT, MICHIGAN, A CORPORATION OF MICHIGAN

STRAINER

Application filed February 25, 1928. Serial No. 256,833.

My invention relates to new and useful improvements in strainers or filters, and more particularly to a strainer or filter adapted for embodiment in a liquid conducting pipe line or other conduit.

An object of my invention is to provide a strainer having a large filtering area or surface.

Another object is to provide a strainer which will not trap air.

Still another object is to provide a strainer which is efficient in operation and of simple construction.

The invention consists in the improved construction and combination of parts, to be more fully described hereinafter, and the novelty of which will be particularly pointed out and distinctly claimed.

In the accompanying drawing, to be taken as a part of this specification, I have fully and clearly illustrated a preferred embodiment of my invention, in which drawing—

Figure 1 is a top plan view of my improved strainer;

Fig. 2 is a vertical central section on the line 2—2 of Fig. 1;

Fig. 3 is a detail plan section on the line 3—3 of Fig. 2;

Fig. 4 is a detail section in elevation on the line 4—4 of Fig. 1, and

Fig. 5 is a detail section in elevation on the line 5—5 of Fig. 1.

Referring to the drawing by characters of reference, 1 designates generally a hollow casing having a side wall 2, preferably substantially cylindrical, and having a head or upper end wall 3 and an open lower end 4. The inside face 3^a of the wall 3, preferably slopes or is inclined slightly upward from the side wall 2 toward its center, so that it is substantially concave. Depending substantially centrally from the face 3^a of the wall 3, is a boss 5 having a bore 6 forming a sleeve which is internally threaded and coaxial with the longitudinal axis of casing 1. Abutting the annular end of boss 5 is a supporting plate 7 having a central aperture 7^a therethrough which is aligned with bore 6. The plate 7 is preferably substantially in the form of an inverted truncated hollow cone, the base of

which lies adjacent to but spaced from the wall 3. Inserted through aperture 7^a and threaded into bore 6 of the sleeve or boss is one end of a post or rod support member 8 having a peripheral shoulder 9 which abuts and supports the plate 7 and serves to tightly clamp the same against the end of the sleeve boss 5. The rod or post 8 may be polygonal intermediate its ends for application of a wrench thereto. A suitable gasket 10 may be inserted between the shoulder 9 and plate 7, if desired, to seal the joint. Secured and sealed to the periphery of the plate 7, as at 10^a, and depending therefrom in spaced relation to the side wall 2, is a foraminous element 11 which is preferably cylindrical and a screen of fine wire mesh which extends downward substantially to the open casing end 4. The free end of the screen or element 11 has secured and sealed thereto, as at 11^a, a surrounding flange 12 which overlies the end of the side wall 2 at the open end 4 of casing 1. The post 8 extends beyond or out of the open end 4 of casing 1, and is threaded at its free end 13. Closing the open end 4 of casing 1, is a cap member 14, which is substantially cup-shaped, having an annular shoulder 15 on which the flange 12 seats, and also having a surrounding rim or flange 16 which surrounds the free end of side wall 2. Between the end of wall 2 and the flange 12, and also between the shoulder 15 and flange 12, I preferably place gaskets 17 and 18, respectively. Centrally through the cap member 14 is an aperture 19, through which the free end 13 of post 8 slidably passes. Threaded on the free end 13 of post 8 is a cap nut 20 which engages the cap member 14 to tightly clamp the flange 12 between the shoulder 15 and the end of wall 2. In the cap-engaging end of the nut 20 is an annular recess 21 in which is a gasket 22 which abuts the cap member 14 to seal the joint between nut 20 and member 14. Through the head 23 of nut 20 is an internally threaded aperture 24 which receives a screw plug 25 having a suitable gasket 26 to engage the head 23 and prevent leakage through aperture 24. The cap member 14 may be provided with internal reinforcing ribs 27, if desired. The end 13 of post 8 has an axial

passage 28 therein, which opens into a passage 29 extending transversely through post 8 within the cap member 14. At its opposite end the post 8 has an axial passage 30 which extends beyond shoulder 9 and opens into a passage 31 which extends transversely through the post 8 and which communicates at its ends with the interior of the cylindrical screen 11.

External of the casing 1 but on the head or end wall 3 is a boss, generally designated at 32 and comprising a valve casing having a central portion 33 from which extend arm portions 34, 35. The portion 33 has a cylindrical recess 36 serving as a valve chamber which is concentric with the casing 1. Opening through the base 37 of the recess 36 is a passage 38 communicating with the bore 6 and post passage 30. Also in the boss 32 and opening through the base 37 are a plurality of passages 39, 40 and 41. The passage 39 extends downward through the end wall 3 where it opens at the highest point in the wall into the space in casing 1 around or external of the screen 11. The passages 40, 41 connect, respectively, with an inlet passage 42 and an outlet passage 43, which are respectively in the arm portions 34, 35. The passages 42, 43 are respectively internally threaded, as at 44, 45, for connection of the strainer in a pipeline or conduit (not shown). Seated on the base 37 is a disk valve member 46 of a diameter substantially equal to the diameter of the cylindrical recess 36. In the upper face of the disk member 46 is a diametrical slot 47. Through the member 46 is an axial aperture 48 which opens at one end into the slot 47, and at the other end communicates with the passage 38. The periphery of the disk member 46 has an arcuate recess 49 into which projects, from the base 37, a stop pin 50 secured in a socket 51 in the central boss portion 33. Through the member 46 is an aperture 52 adapted to register with passage 40, and in the underside of the disk member is an arcuate slot or passage 53 into the opposite ends of which the passages 39 and 41, respectively, open when the passage 40 and aperture 52 are in register. Threaded into the recess 36 is a sleeve or bonnet member 54 having a surrounding flange 55 adapted to seat on the end of portion 33 and between them may be placed a gasket 55a. The member 54 has a longitudinal bore 56 which is of enlarged diameter, as at 57. Journalled in the bore 56 is a valve stem 58 having a surrounding flange 59 which abuts the inner end or under side of the sleeve member 54. The stem 58 projects outward beyond the sleeve member 54, and at its inner end has an axial recess or socket 60. Coaxial with the aperture 48 is a cylindrical recess 61 in the top of disk member 46 and also in alinement with the socket 60. Positioned between the stem 58 and member 46 is a resilient member

62, preferably a spring of the coil type, having its ends respectively seated in the recesses 60 and 61, and held under compression therebetween whereby the spring serves to hold the flange 59 against sleeve member 54, and to hold the disk member 46 against the recess base 37, which serves as a valve seat. Depending from the stem 58 are operating members or fingers 63 which project into the slot 47, but only to a portion of its depth so as to provide flow passages beneath the fingers 63, as at 64. Within the enlarged bore portion 57 of sleeve member 54 is a suitable packing medium 65, which is expanded radially to prevent leakage around the stem 58 by a packing sleeve 66 which surrounds stem 58, and which is forced into engagement with the packing medium by a packing nut 67 threaded on the sleeve member 54, as at 68.

The operation of the strainer is as follows: The strainer having been connected in a liquid line by means of the inlet and outlet passages 42, 43, respectively, and the disk member 46 having been rotated by means of stem 58 to align passage 40 and the valve port or aperture 52, which alinement is determined by the end of arcuate slot 49 bringing up against the stop pin 50 and preventing further counterclockwise rotation of the disk member 46, as is apparent from Fig. 3; then liquid in the line will flow from inlet 42 through passage 40 and aperture 52 into chamber 36, thence into slot 47 and beneath fingers 63 to post passages 30 and 31, thus filling the casing 1. Within the casing 1 the liquid will filter through screen element 11, and when the casing 1 is filled will flow through passage 39, arcuate slot 53 and passage 41 to the outlet 43 and the line. If the stem 58 is rotated clockwise till the opposite end of slot 49 abuts pin 50, then passages 40 and 41 will be closed. Any sediment or foreign matter in the liquid will collect in cap member 14, and by removing screw 25 may be drained therefrom, or by removing nut 20 and screw 25 together, the cap member 14 may be slipped off post 8 for cleaning.

The strainer is particularly adapted, among other uses, to be employed in the oil feed line of a liquid fuel burning apparatus which is provided with an oil suction pump. Due to the construction of the strainer, namely, the centrally upward sloping wall 3, the admission point from the inlet passage 30 to casing 1 being below the emission point from the casing through passage 39, the upwardly and outwardly flaring plate 7, and the passage 39 leading off from the casing 1 at its point of greatest internal height, it is apparent that the strainer will not trap air. Any air in the line or in the casing 1 will be forced out of the casing ahead of the oil and will not be pocketed in the casing 1 to be released later, for example, on a drop of oil level or a decrease of line pressure as the

suction increases, which would cause the air to expand, and in either case pass air to the pump, thereby causing the pump to lose its prime.

5. What I claim and desire to secure by Letters Patent of the United States is:—

1. A device of the character described, comprising a hollow casing having an end wall, a sleeve having a longitudinal bore and depending from said wall, an upwardly and outwardly flaring plate overlying the free end of said sleeve and having a central aperture alined with said bore, means to seal said plate to said sleeve, a strainer element secured to and sealed along the periphery of said plate, and an outlet passage leading from the interior of said casing through said end wall. 70

2. A device of the character described, comprising a hollow casing having an end wall, a sleeve having a longitudinal bore and depending from said wall, a plate overlying the free end of said sleeve and having an aperture alined with said bore, a support member to seal said plate to said sleeve, said member having a transverse open-ended passage therethrough, a passage in said member opening into said bore and terminating in said transverse passage, a strainer element secured to and sealed along the periphery of said plate, an outlet passage leading from the interior of said casing through said end wall, and valve means carried by said end wall to close said outlet passage. 75

3. A device of the character described, comprising a hollow casing having a concave end wall, a sleeve having a longitudinal bore and depending from said wall, an upwardly and outwardly flaring plate overlying the free end of said sleeve and having an aperture alined with said bore, means to seal said plate to said sleeve, a strainer element secured to and sealed along the periphery of said plate, and an outlet passage leading from the interior of said casing through the highest point of said end wall whereby said casing will not trap air. 100

4. A device of the character described, comprising a hollow casing having an end wall, said end wall having a valve chamber and an inlet passage and an outlet passage, each of said passages opening into said casing and into said chamber, said outlet passage terminating at an opening upward from the inside face of said wall whereby to prevent trapping of air in the casing said chamber having an inlet and an outlet, valve means in said chamber adapted to close said inlet, and a strainer element in said casing interposed between said inlet passage and said outlet passage. 105

5. A device of the character described, comprising a hollow casing having an end wall, said end wall having a valve chamber and an inlet passage and an outlet passage, each of said passages being formed in said 110

end wall and opening into said casing and into said chamber, said outlet passage terminating at an opening upward from the inside face of said wall whereby to prevent trapping of air in the casing said chamber having an inlet and an outlet, valve means in said chamber adapted to close said inlet and said outlet simultaneously, said valve means having an aperture therethrough registerable with said inlet for flow into said chamber and a strainer element in said casing interposed between said inlet passage and said outlet passage. 115

6. A device of the character described, comprising a hollow casing having an end wall, a boss on said wall external to said casing, said boss having a substantially cylindrical recess, an inlet passage opening from said recess through said end wall into said casing, an outlet passage opening from said casing through said end wall into said recess, an inlet to said recess and an outlet from said recess, a movable valve member in said recess, said member having an aperture therethrough alined with said inlet passage, a second aperture through said member adapted to aline with said inlet to permit communication between said inlet and said aperture, said valve member having a passage therein adapted to permit communication between said outlet passage and said outlet when said second aperture and said inlet are in register, means to move said valve member to place said inlet and said second aperture into and out of registry, and a strainer element within said casing interposed between said inlet passage and said outlet passage. 120

7. A device of the character described, comprising a hollow casing having a substantially cylindrical side wall and having a substantially concave end wall and an open end, a boss depending centrally from said wall and having a longitudinal bore, a support member secured in said bore, an upwardly and outwardly flaring plate clamped between said member and said boss, a substantially cylindrical screen secured and sealed at one end to the periphery of said plate and depending to the open end of said casing, a lateral surrounding flange on the free end of said screen overlying the end of said side wall, a cap member closing said open casing end and engaging said flange, means carried by said support member and acting on said cap member to clamp said flange between said side wall and said cap member, an inlet passage opening into said cylindrical screen through said boss and said plate, and an outlet passage opening from said casing external of said screen and through said end wall. 125

8. A device of the character described, comprising a hollow casing having a substantially cylindrical side wall and having a substantially concave end wall and an open end, a boss depending centrally from said wall 130

and having a longitudinal bore, a support member secured in said bore, an upwardly and outwardly flaring plate clamped between said member and said boss, a substantially cylindrical screen secured and sealed at one end to the periphery of said plate and depending to the open end of said casing, a lateral surrounding flange on the free end of said screen overlying the end of said side wall; a cap member closing said open casing end and engaging said flange, means carried by said support member and acting on said cap member to clamp said flange between said side wall and said cap member, an inlet passage opening into said cylindrical screen through said boss and said plate, an outlet passage opening from said casing external of said screen and through said end wall, a valve chamber communicating with said inlet and said outlet passages, a valve in said chamber adapted to open and close one of said passages, and means engaging said valve whereby said valve may be operated.

9. A device of the character described, comprising a hollow casing having an end wall and an open end, a plate member, a strainer element secured and sealed to the periphery of said member and depending therefrom in laterally spaced relation to said casing and substantially to the open end of said casing, a supporting member clamping said plate member to said end wall, a cap member closing the open end of said casing and securing and sealing the free end of said element to said casing, means engaging said supporting member to secure said cap member to said casing, said casing having an inlet passage and an outlet passage, one of said passages opening within said element, and the other of said passages opening between said element and said casing.

10. A device of the character described, comprising a hollow casing having a strainer element therein, said casing having a valve chamber and passages opening from said chamber into said casing on opposite sides of said element, said casing having an inlet to said chamber and an outlet from said chamber, a valve member in said chamber having an aperture therethrough in constant communication with one of said passages, said valve member having a second aperture movable into and out of registry with said inlet, said valve member having a passage operable to permit communication between said outlet and the other of said passages, and means to operate said valve member.

11. A device of the character described, comprising a hollow casing having a strainer element therein, said casing having a valve chamber and passages opening from said chamber into said casing on opposite sides of said element, a bonnet closing said chamber, a rotatable disk valve member in said chamber to control said pas-

sages, a valve stem journaled in said bonnet and having means engaging said valve member to rotate said valve member, a flange on said stem engaging the under side of said bonnet, and spring means abutting said stem and said valve member to seat said valve member and hold said flange in engagement with said bonnet.

12. A device of the character described, comprising a hollow casing having an end wall with a recess therein having a bottom wall, said end wall having an inlet and an outlet opening into said recess through said bottom wall, said end wall having passages opening into the interior of said hollow casing and into said recess through said bottom wall, valve means in said recess controlling communication between said inlet and one of said passages and between another of said passages and said outlet, and a strainer element within said hollow casing and interposed between said passages.

In testimony whereof I have hereunto subscribed my name.

CERTIFICATE OF CORRECTION.

Patent No. 1,892,190.

December 27, 1932.

PHILIP SHERMAN RUSSEL.

It is hereby certified that error appears in the printed specification of the above numbered patent requiring correction as follows: Page 3, lines 53 and 68, claims 4 and 5, respectively, for "an" read "and"; and lines 55 and 70, claims 4 and 5, respectively, after "casing" insert a "comma"; and that the said Letters Patent should be read with these corrections therein that the same may conform to the record of the case in the Patent Office.

Signed and sealed this 28th day of February, A. D. 1933.

(Seal)

**M. J. Moore,
Acting Commissioner of Patents.**
